UNITED STATES PATENT OFFICE.

HERBERT M. DAWLEY, OF BUFFALO, NEW YORK, ASSIGNOR TO THE PIERCE-ARROW MOTOR CAR COMPANY, OF BUFFALO, NEW YORK.

WINDOW CONSTRUCTION.

1,115,056.

Specification of Letters Patent. Patented Oct. 27, 1914.

Application filed March 27, 1913. Serial No. 757,074.

To all whom it may concern:

Be it known that I, HERBERT M. DAWLEY, a citizen of the United States, residing at Buffalo, in the county of Erie and State of New York, have invented a new and useful Improvement in Window Constructions, of which the following is a specification.

This invention relates to improvements in window constructions, more particularly for automobiles and other vehicles which are provided with folding windows adapted to be moved from an inoperative position in which they are out of the way to an upright or operative position in which they constitute portions of the inclosing tops of the vehicles.

The objects of the invention are to produce a window of practical and desirable construction having a folding or hinged frame, or frame section, adapted to be moved into and out of upright operative position, and provided with a sliding sash or window glass adapted to be adjusted to any desired position in the folding frame; also to provide means for holding the folding frame rigidly and locking it in the operative position; also to provide means for positively preventing the sliding sash from being operated unless the folding frame is locked in its operative position and for preventing the folding frame from being unlocked and folded unless the sliding sash has first been moved out of the folding frame, so as thereby to avoid the possibility of breaking the window glass; and also to improve folding windows in the respects hereinafter described and set forth in the claims.

In the accompanying drawings, consisting of three sheets: Figure 1 is an inside elevation of a vehicle door provided with a folding window embodying the invention, the inner cover of the door being removed to expose the sash operating mechanism. Fig. 2 is an edge elevation thereof. Fig. 3 is a transverse vertical sectional elevation thereof. Fig. 4 is a similar view showing the window partly folded. Fig. 5 is a longitudinal sectional elevation, enlarged, in line 5-5, Fig. 4. Fig. 6 is an enlarged sectional elevation of the window locking device in line 6-6, Fig. 1. Fig. 7 is a sectional plan in line 7-7, Fig. 6, showing the locking de-

vice released. Fig. 8 is a similar view showing the locked position of the parts. 55

Like reference characters refer to like parts in the several figures.

In this application the invention is illustrated and described in connection with the door of the open or touring body of an automobile, the window being hinged to the top of the door, so that it is adapted to be secured in an upright operative position in which it constitutes the upper portion of the door and the closure for the door opening in the vehicle top, or to be folded downwardly at the inner side of the door when the vehicle top is lowered for opening the vehicle. The window is, however, also adapted for use for other purposes and in other places, 70 as for instance, to form the folding front or partition of a closed vehicle or other structure.

A represents the vehicle door which may be of ordinary construction consisting of a 75 substantially rectangular frame, and outer and inner walls or cover plates.

a indicates the outer cover plate.

The inner cover or lining is omitted in the drawings to expose the window operating mechanism.

Since the door or part A constitutes the lower or relatively stationary portion of the window casing or frame and, in so far as this invention is concerned, could just as 85 well be a stationary casing, it will be hereinafter designated as a casing.

B represents the folding or hinged window frame which, as shown, consists of upright side bars connected by a horizontal 90 top bar. This frame is hinged to the top of the casing A by hinges C of any suitable kind connected to the lower ends of the side bars of the frame B, which will permit the frame to be secured in an upright operative 95 position over the casing A, as shown in Figs. 1-3, or to be folded downwardly at the inner side of the casing. The hinged frame is held rigidly in the upright position by jointed braces D having their upper ends 100 suitably pivoted at d to the side bars of the hinged frame and their lower ends suitably pivoted at d' to the casing A. The lower ends of the braces are preferably pivoted to brackets d² projecting from the inner face 105 of the casing while their upper ends enter

and are pivoted in rabbets d^3 in the side edges of the hinged frame B, as thereby the braces incline toward the hinged frame when the latter is in the upright position and hold it more rigidly and firmly. When the hinged frame is swung downwardly the folded braces are received in spaces formed by the rabbets d^3 and, therefore, do not prevent the hinged frame from swinging in close to the casing A.

E represents a window pane or glass which is arranged to slide vertically in a suitable cavity in the casing A and is adapted to be raised through a slot in the top thereof into the hinged frame B when the frame is in the upright operative position. A light frame or sash formed of thin metal channel strips e preferably embraces the sides and bottom edges of the window glass.

While the glass framed in this way is shown and for the sake of clearness of description is referred to herein as a sash, the frame is not absolutely necessary and the term sash is intended to cover the sliding glass or pane, whether or not it is provided with a frame. The window sash is guided in its movements by vertical channels or ways e' in the casing and channels or ways e'' on the inner edges of the side bars of the hinged frame which register with and form continuations of the channels e' when the frame B is in the upright position. Preferably the guide ways in the casing and hinged frame are lined with suitable material, indicated at e'', Fig. 7, to prevent the window glass from rattling, and the top bar of the hinged frame B is formed in its lower edge with a groove e''' provided with a bumper strip e'' for the same purpose and for making a weather tight joint.

For raising and lowering the sliding sash the following elevating mechanism is employed:—F represents a chain which passes around sprocket wheels f, f' journaled in any suitable manner, one above the other, in the interior of the casing A. The shaft of the wheel f is provided with an exposed handle f'' for turning it and the chain F. A stud or roller f''' projects from the chain into a slotted plate f'' secured to the lower edge of the sliding sash so that by turning the handle f'' in one direction or the other the sash is raised or lowered.

In order to prevent the window glass from being broken or injured in operating the folding window frame B, locking means are employed in connection with the sash elevating mechanism which lock the window braces D for preventing the hinged frame from being moved from its upright position until the sash is first lowered completely into the casing and lock the window elevating mechanism for preventing the sash from being raised unless the hinged frame is secured in the upright operative position. In

the means shown for this purpose the braces D are provided with hooks G which, when the braces are straightened to secure the frame B in its upright position, project into holes g in lock plates g' secured to the casing A, and are engaged by sliding bolts H H' for locking the braces. The lock plates g' are conveniently formed by the lower leaves of the hinges C for the folding window frame, but this is not necessary. The bolts H H' are slidably mounted in the interior of the casing in any convenient guides h and are connected by a centrally pivoted lever h' for causing the simultaneous movement of the two bolts in opposite directions. When the bolts are moved outwardly, or away from each other, their outer ends enter notches h'' in the hooks G thereby locking the braces D. The bolts are shifted into and out of locking position by a stud I on the chain F which is adapted to engage a notched plate or part i secured to the bolt H at a point over the chain wheel f. During the last portion of the movement of the chain F in the direction to lower the sash the stud I enters the notch of the plate i and shifts the bolts inwardly, so as to withdraw their ends from the notches in the brace hooks G thus releasing the braces and permitting them to be operated to fold the hinged frame B. When the elevating chain is moved in the opposite direction for raising the window glass, the stud I moves the plate i, projecting the bolts H H' into the notches of the hooks G and locking the braces D. After a short initial movement of the chain sufficient to actuate the bolts H H' the stud I passes out of engagement with the notched plate i, thus permitting the continued movement of the chain and the elevation of the window sash.

K represents stop blocks which are suitably pivoted on the lock plates g' at the inner ends of the holes g in position to be engaged and moved by the hooks G in entering said holes. These stops are normally held by springs k of any suitable kind against the inner face of the lock plate in the path of the bolts H H' and prevent the movement of the bolts to the locking position. When the braces D are straightened to secure the hinged window frame in the upright position, the hooks G entering the holes g shove the stops K out of the path of the bolts, and the bolts can then be slid to lock the braces, but when the braces are bent to lower the folding frame, thereby withdrawing the hooks G from the holes g, the stops K will be moved by their springs into the path of the bolts H H' and prevent the movement of the bolts. Since the stud I on the elevating chain F is engaged and held by the notched plate i on the bolt H when the bolts are in the released position the chain cannot be operated to raise the

window glass. The hooks G themselves will obstruct the movement of the bolts H H' if they are only partially inserted into the holes g. It is, therefore, impossible to raise the window glass unless the folding frame is rigidly secured in the upright position by the straightened braces.

I claim as my invention:

1. The combination of a window frame comprising a relatively stationary part, and a folding part which is hinged to said stationary part to swing from an upright operative position to a folded position, means for securing said folding frame part in its upright position, a window sash which is slideable vertically in said stationary and folding frame parts when the latter is in its upright position, and means which lock said sash from movement except when said hinged frame part is secured in its upright position.

2. The combination of a casing, a folding window frame which is hinged to said casing to swing from an upright operative position to a folded position, a window sash which is slideable vertically in said casing and frame when the latter is in upright position, means mounted on said casing for operating said sliding sash, and means for locking said sash from movement except when said hinged frame has been moved fully to the upright operative position, substantially as set forth.

3. The combination of a casing, a folding window frame which is hinged to said casing to swing from an upright operative position to a folded position, a window sash which is slideable vertically in said casing and frame when the latter is in upright position, means for securing said hinged frame in the upright position, and means cooperating with said securing means which prevent the operation of said sash except when said securing means are in securing position, substantially as set forth.

4. The combination of a casing, a folding window frame which is hinged to said casing to swing from an upright operative position to a folded position, a window sash which is slideable vertically in said casing and frame when the latter is in upright position, means for securing said hinged frame in the upright position, and means controlled by said securing means for locking said sash from movement except when said hinged frame is secured in upright position, substantially as set forth.

5. The combination of a window frame comprising a relatively stationary part and a part which is movable to and from operative relation to said stationary part, a window sash which is slideable in said frame, means for securing said movable frame part in the operative position, operating means for said sliding sash, and locking means for said operating means which are released by

securing said movable frame part in operative position, substantially as set forth.

6. The combination of a window frame comprising a relatively stationary part and a part which is movable to and from operative relation to said stationary part, a window sash which is slideable in said frame, means for securing said movable frame part in the operative position, operating means for said sliding sash, locking means for said operating means, and securing means for said movable frame part which release said locking means when the securing means are moved to securing position, substantially as set forth.

7. The combination of a window frame comprising a relatively stationary part and a part which is movable to and from operative relation to said stationary part, a window sash which is slideable in said frame, means for securing said movable frame part in the operative position, operating means for said sash, and means controlled by said operating means for locking said frame securing means in securing position, substantially as set forth.

8. The combination of a casing, a folding window frame which is hinged to said casing to swing from an upright operative position to a folded position, a window sash which is slideable vertically in said casing and frame when the latter is in upright position, means for locking said hinged frame in upright position, and means which are operated to release said locking means by the sliding of said sash out of said hinged frame, substantially as set forth.

9. The combination of a window frame comprising a relatively stationary part and a part which is movable to and from operative relation to said stationary part, a window sash which is slideable in said frame, means for securing said movable frame part in the operative position, locking means for said frame-securing means, and means which are operated to release said locking means by the sliding of said sash out of said movable frame part, substantially as set forth.

10. The combination of a window frame comprising a relatively stationary part and a part which is movable to and from operative relation to said stationary part, a window sash which is slideable in said frame, means for locking said movable frame part in operative position, means which are operated to release said locking means by the sliding of said sash out of said movable frame part, means for locking said sash from movement in said frame, said sash locking means being released by the movement of said movable frame to the operative position, substantially as set forth.

11. The combination of a hinged window frame adapted to swing from an operative to an inoperative position, a brace for secur-

ing said hinged frame in the operative position, a sash arranged to slide in said hinged frame, and means controlled by said brace for locking said sash from movement, substantially as set forth.

12. The combination of a hinged window frame adapted to swing from an operative to an inoperative position, a brace for securing said hinged frame in the operative position, a sash arranged to slide in said hinged frame, operating means for said sash, and means controlled by said brace for preventing the operation of said sash operating means, substantially as set forth.

13. The combination of a hinged window frame adapted to swing from an operative to an inoperative position, a brace for securing said hinged frame in the operative position, a sash arranged to slide in said hinged frame, operating means for said sash, and locking means for said brace controlled by said operating means, substantially as set forth.

14. The combination of a hinged window frame adapted to swing from an operative to an inoperative position, a brace for securing said hinged frame in the operative position, a sash arranged to slide in said hinged frame, a locking device for said brace, and elevating means for said sash which release said locking device when said sash is moved out of said hinged frame, substantially as set forth.

15. The combination of a hinged window frame adapted to swing from an operative to an inoperative position, a brace for securing said hinged frame in the operative position, a sash arranged to slide in said hinged

frame, operating means for said sash, and a locking device which is moved by said operating means to lock said brace during the first portion of the operative movement of said operating means, substantially as set forth.

16. The combination of a hinged window frame adapted to swing from an operative to an inoperative position, a brace for securing said hinged frame in the operative position, a sash arranged to slide in said hinged frame, operating means for said sash, a locking device which is moved by said operating means to lock said brace, and a stop which in one position thereof prevents the movement of said locking device and said operating means, said stop being moved from said position by said brace when the brace is moved into position to secure said frame, substantially as set forth.

17. The combination of a window frame comprising a relatively stationary part and a part which is movable to and from operative relation to said stationary part, a window sash which is slideable in said frame, means for securing said movable frame part in the operative position, and means cooperating with said securing means for preventing the operation of said sash except when said movable frame part is secured in the operative position, substantially as set forth.

Witness my hand, this 24th day of March, 1913.

HERBERT M. DAWLEY.
